Patented Dec. 1, 1914.

UNITED STATES PATENT OFFICE.

ROBERT REACH, OF SPRINGFIELD, MASSACHUSETTS.

STRIKING-BAG.

1,119,635.

Specification of Letters Patent.

Patented Dec. 1, 1914.

Application filed December 3, 1912. Serial No. 734,769.

To all whom it may concern:

Be it known that I, ROBERT REACH, citizen of the United States, residing at Springfield, Massachusetts, have invented certain new and useful Improvements in Striking-Bags, of which the following is a specification.

It is the object of my invention to provide means for suspending a striking bag which will allow the same all necessary swinging and swiveling movement and will present a simple and durable construction.

The invention consists in the features, combination and arrangement of parts hereinafter described, and particularly pointed out in the claims.

In the accompanying drawings,—Figure 1 is a side view of a part of the bag with the improved suspending means combined therewith. Fig. 2 is a central vertical section of Fig. 1. Fig. 3 is a detailed view of the suspending socket or shell.

In carrying out my invention I secure or form on the lower end of the suspending cord 1, an enlargement 2, consisting in the present instance of a ball or sphere which is held to the cord by a pin or screw 3. This ball fits within a socket or shell 4 having its upper end of partial spherical formation at 5 to afford a proper seat for the ball, an opening 6 being provided at the upper end of the socket or shell for the passage of the cord and of sufficient area to allow the socket or shell to turn on the ball under all the conditions to which the striking bag is subjected.

The socket piece or shell is flared outwardly at its lower end into substantially the shape of a bell as at 7. This bell shaped portion fits within the neck 8 of the striking bag, which neck is slotted at 9 at one or more points and is bordered by any suitable binding material or bead 10. This beaded neck extends up along the bell shaped shell or socket piece to about midway of its height or slightly higher and which is at about the point of narrowest diameter of the bell. The neck of the bag is held on this bell shaped piece by a strap or draw string 11 which passes through eyes 12 formed by cutting out portions of the covering of the striking bag and passing the strap under these cut out portions. The lower edge of the bell or socket piece is rolled as at 13 and this is true also of the upper edge 14. Between the bell and the expandable portion of the striking bag a washer of leather or

suitable material 16 is placed, such washer being of substantially conical form and having an aperture 17 through which projects the tube 18 by which the expandable inner portion is inflated.

It will be seen from the above construction that the ball is adapted to turn freely in the socket or bell shaped member, which I prefer to form of metal and preferably of aluminum, and it will also be seen that this bell shaped member affords a shaping and foundation member for the neck of the cover of the bag, which being secured firmly by the strap around the narrow portion of the bell shaped part, is held thereto with sufficient security to withstand all the blows to which the striking bag is subjected.

The washer 16 serves to protect the inner inflatable portion of the bag from contact with the edge of the bell and in effect it forms an extension of the retaining cover of the bag, its edges being held firmly under the edge of the bell shaped part and against the outer covering.

Instead of securing a ball on the lower end of the suspending cord, I may provide any other suitable enlargement, consisting for instance of a knot formed on the end of the said cord, though of course I prefer the body of spherical form.

Besides protecting the inner inflatable member 19 from contact with the metal bell shaped member, the washer performs an additional important function in that it forms practically a continuation over the top of the inflatable member of the walls of the outer leather covering and renders it possible to remove the ball and bell without deflating the inner member. It will be noticed that when the bag is inflated the edge of the washer is clamped between the inner member and the outer covering, and as it extends over the inner member it restrains it from blowing up into the metal socket member, and should this socket member be removed the washer will still restrain the inner member against blowing out through the neck of the cover. This washer is simply slipped over the filling tube in placing it in position and it is not necessary to attach it to the cover or to the inner member.

I claim as my invention:

1. In combination with the cover of a striking bag, a bell shaped member fitting in the neck thereof, means for securing the neck of the cover at the narrow part of the

- bell shaped member, and a suspending cord, said bell shaped member having a swivel connection with the said cord, substantially as described.
5. In combination in a striking bag, a bell shaped member, a cover having a portion surrounding the bell shaped member a cord connected therewith, and a strap passing through a slitted portion of the neck for holding the same to the bell shaped member, substantially as described.
10. 3. In combination in a striking bag, a suspending cord, a cover having a neck, a member held within the neck with connection between the said member and suspending cord, and a washer between the said member and the inner inflatable portion of the bag, and borne upon by said member and inflatable portion substantially as described.
15. 4. In combination in a striking bag, a cover having a neck, a bell shaped shell therein, a suspending cord a swivel connection between the said bell shaped shell and the suspending cord, and a washer extending over the upper end of the inner inflatable part of the bag and beneath the edge of the bell shaped shell, substantially as described.
20. 5. In combination in a striking bag, suspending means, a bell shaped member supported thereby, a cover, and means for securing the cover to the bell shaped member below the suspending means.
25. 6. In combination a cover having a neck, a bell member within the neck, a suspending cord connected with the bell member, an inflatable member within the cover, said bell member being removable from the neck, and a washer having its lower edge held between the inflatable member and the cover, and extending over the top of said inflatable member to prevent the same from protruding into the bell member or neck of the cover, substantially as described.
30. 7. In a striking bag, suspending means, a cover, an inflatable member, a bell shaped member, and means for confining the cover to the bell shaped member intermediate of the suspending means and the inflatable member.
35. 8. In combination in a striking bag, an inflatable member, a cover therefor having a neck, a shell held by the neck of the cover, and a suspending cord having an enlargement at its lower end, said enlargement being fixed non-rotatively in relation to the cord and engaging directly and swiveling within the shell, substantially as described.
40. 9. In combination in a striking bag, an inflatable member, a cover therefor having a neck, a sheet metal bell shaped shell arranged in the neck and having its upper and lower rims rolled, a suspending cord having an enlargement at its end within the shell, means for securing the neck of the cover to the shell, and a protecting layer of material between the lower edge of the shell and the inflatable member, substantially as described.
45. 10. In combination in a striking bag, a suspending cord, a ball carried thereby, a bell shaped socket supported by the ball, a bag carried by the bell shaped piece, and means for confining the end of the bag to the bell below the position of the ball.
50. 11. In combination in a striking bag, an inflatable member, a cover having a neck, a rigid bell-shaped member held in the neck of the cover, a suspending cord having an enlargement held in the bell-shaped member, and a washer extending over the inflatable member and held at its lower edge to prevent the protrusion of the inflatable member into the rigid bell, substantially as described.
55. 12. In a striking bag, suspending means, an inflatable member, a bell shaped member supported by said suspending means, a cover, and confining means carried by the cover for holding the cover and bell shaped member together and permitting when released the removal of the said member and suspending means independently of the deflation and removal of the inflatable member.
60. ROBERT REACH.
